UNITED STATES PATENT OFFICE.

CARL HOCHENEGG, OF VIENNA, AUSTRIA-HUNGARY, ASSIGNOR TO SIEMENS & HALSKE ELECTRIC COMPANY OF AMERICA, OF CHICAGO, ILLINOIS.

CONTROL SYSTEM FOR ELECTRIC CARS.

SPECIFICATION forming part of Letters Patent No. 683,279, dated September 24, 1901.

Application filed January 22, 1900. Renewed August 2, 1901. Serial No. 70,781. (No model.)

To all whom it may concern:

Be it known that I, CARL HOCHENEGG, a subject of the Emperor of Austria-Hungary, residing at Vienna, Austria-Hungary, have 5 invented a certain new and useful Improvement in Electric-Railway Systems, (Case No. 299,) of which the following is a full, clear, concise, and exact description, reference being had to the accompanying drawings, forming 10 a part of this specification.

My invention relates to electric-railway systems, and has for its object the provision of improved means for effecting the operation of controllers upon several motor-cars in a 15 single train and also the provision of improved switching apparatus for controlling the operation of the traction-motors with the supply-conductors and for simultaneously effecting a reversal of the motor connections to 20 reverse the direction of rotation of the traction-motors, and thereby the direction of travel of the train.

More specifically one feature of my invention has for its object the provision of an 25 improved motor means adapted to effect the operation of suitable mechanism upon each of the motor-cars to effect the simultaneous operation of the motor-controllers.

My improved motor means is particularly 30 well adapted to operate the controller-actuating mechanism illustrated in Patent No. 623,223, dated April 18, 1893. In the apparatus disclosed in said patent special electric motors receiving their current from the trolley-line were employed to effect the operation 35 of the controller-actuating mechanism, one motor being placed upon each of the motor-cars, this motor running constantly to be in readiness to operate the controller-actuating 40 mechanism. I have shown my improved motor means as being adapted particularly for use in connection with the apparatus of the said patent; but I do not wish to be limited to the use to which the invention may be put. 45 Generally speaking, this feature of my invention consists in a motor means associated with each motor-controller, the motor means being adapted to be mechanically driven by means of the moving car. The cars in traveling effect the rotary movement of the motor means, preferably through the agency of the rotating axles of the car-trucks, gearing

being preferably interposed between the car-axes and the rotating motor means. Clutch mechanism, preferably that shown in the said 55 patent, is interposed between each motor means and its associate controller.

Another feature of my invention may be generally described as consisting in pole-changing switches associated with the traction-motors and electromagnetic means for effecting the operation of the pole-changing switches, this electromagnetic means being preferably operated by means of current received from the trolley-line. The switches 60 are preferably so disposed with relation to the electromagnetic means for effecting their operation that when the current for supplying this means is interrupted the switches will be in neutral position, in which they 65 serve to cut the motors out of circuit.

I will explain my invention more particularly by reference to the accompanying drawings, in which—

Figure 1 diagrammatically illustrates two 75 motor-cars in the train, the apparatus of my invention being shown in place. Fig. 2 illustrates diagrammatically, two motor-cars in the train, modified means for effecting the operation of the pole-changing switches and for 80 initially controlling the motors being illustrated. Fig. 3 is a plan view of a car-axle with its wheels in place thereon and the preferred form of motor driven by the car-axle. Fig. 4 is a sectional view on line 4-4 of Fig. 85 3. Fig. 5 is a side view of the mechanism shown in Fig. 3.

Like parts are indicated by similar characters of reference throughout the different views.

I will first explain the type of controller-actuating mechanism that is adapted for use 90 in connection with the improved motor means of my invention, after which I will describe my improved motor means in detail and the 95 mechanism for initially controlling the motors and their precise manner of communication with the trolley-line.

I preferably employ upon each motor-car of the train my improved motor means *a*, to 100 be more fully hereinafter described, in addition to the traction-motor, the latter receiving current from trolley-wires *b b* by means of trolleys in contact therewith. The motor

means a are preferably of the same size and are adapted to be rotated at the same speed, and through the agency of intervening gearing a' effect the rotation of the shaft c in a uniform direction. A large gear-wheel d and a small gear-wheel e are provided upon each shaft c . Each gear-wheel d engages a collar f , preferably of non-magnetic material, loosely mounted upon a shaft f' . A flexible coupling f^2 unites the shaft f' with the shaft of a controller to permit the controller-shaft gradually to start from a state of rest. Each wheel e engages a small wheel e' , which in turn rotates a clutch member e^2 , also loosely mounted upon the shaft f' . Each clutch member f is opposed to a clutch member f^4 . Each clutch member e^2 is associated with a clutch member e^3 . The clutch members e^3 and f^4 are splined upon the shaft f' and are capable of longitudinal movement upon the shaft. A coiled spring is interposed between the clutch members e^2 e^3 normally to separate the same. Another coiled spring i is interposed between the member f^4 and a disk-armature i' , preferably mounted upon the shaft f' and having no longitudinal movement thereupon. The latter coiled spring when not counteracted maintains the clutch members $f f^4$ in engagement. The coils $l m$ of the clutch members $e^3 f^4$ are adapted to be included in circuit with a suitable source of current, as the battery k , by means of a switch k' , operated by the motorman.

The apparatus upon the cars shown in Fig. 35 1 are similar and similar letters and numerals of reference have been employed to designate like parts thereof.

In operating the controller only one switch k' upon the leading car is usually employed, 40 the switches upon the other cars being open.

Before describing the particular features of my invention I will first set forth the manner of operation of the controller-actuating apparatus described above in detail.

45 Assuming that the shafts c' are rotated in a uniform direction through the agency of the motor means a in order to effect the operation of the controllers n to cut out the resistance from circuit with the armatures and fields of the series-wound traction-motors shown, the switch k' upon car No. 1 is engaged with contact-button 1, circuit from the battery k being thereby closed through the coils $l m$, whereby the clutch-collars $e^2 e^3$ upon 50 each car are engaged and each clutch member f^4 attracted toward its armature i' to disengage it from its companion member f . Each controller is thereupon slowly operated by the wheels e and e' to cut the resistance out 55 of circuit with the traction-motors. When the train has reached the desired speed or when it is stationary, the switch k' is thrown upon button 2, circuit through coils l being thereby opened while current from the battery k continues to flow through the coils m . Upon this operation of the switch the clutch 60 members $e^3 e^3$ upon each car are separated,

so that no motion is communicated from the shafts c to the shafts f' , the parts $e^2 f$ being the only ones upon the shaft f' that are constantly rotated. When it is desired to cut the traction-motors out of circuit, the switch k' is moved to button 3 to open circuit through the coils m , the spring i thereupon throwing the clutch members $f f^4$ of each clutch into engagement, the wheels d then serving to rotate the shafts f' at a rapid speed to cut the traction-motors out of circuit. After the train has been brought to a stop the switch k' is again thrown upon button 2, current from 80 battery k being again directed, through the coils m , to separate the members $f f^4$ upon each car.

I will now describe my improved motor means for effecting the operation of controller-actuating mechanism.

Car-axle o is caused to rotate the motor means, preferably by means of the mechanism illustrated in Figs. 3, 4, and 5. In Figs. 1 and 2 I have shown friction-disks p in frictional engagement with the car-wheels to effect the operation of the motor means a , but this is not the preferred construction. In Fig. 2 the connections between the friction-disks p and the controller-shafts are indicated diagrammatically; but I prefer to employ the controller-actuating mechanism shown in Fig. 3.

Referring to the preferred embodiment of my improved motor means shown in Figs. 3, 4, and 5, I mount a gear-wheel q upon a car-axle and mesh a pinion r into engagement therewith. This pinion serves to rotate a bevel-gear s , which in turn serves to rotate the bevel-gears $t t$. The bevel-gears t are rotated in opposite directions by the bevel-gear s , each of the bevel-gears t having one direction of rotation upon the forward travel of the train and a reversed direction of rotation upon backward movement of the train. The 105 bevel-gears $t t$ are loosely mounted upon a shaft or other rotating part u , which supports a worm a' , Fig. 1, engaging the shaft c . A ratchet v , provided with two sets of teeth sloping in the same direction, is rigidly secured upon the shaft u . The bevel-gears t are provided with pawls w , which engage the teeth of the ratchet, one of the pawls engaging the teeth to effect the rotation of the ratchet, while the other pawl, rotating in the 110 opposite direction, slips engagement with the ratchet-teeth. These pawls are pressed toward the ratchet by means of suitable springs in a manner well known. By means of the gear-wheels $s t t$ and the ratchet v the shaft 115 u is rotated in a uniform direction irrespective of the direction of travel of the train. I am thus enabled to employ motor means for effecting the operation of the controllers, which receive their power as a result of the 120 movement of the train, so that the motor means may be efficient in operation and cheap in construction.

I will now describe my improved means for

initially effecting the control of the traction-motors by reference to Figs. 1 and 2.

I have shown a centrally-pivoted pole-changing switch x , one end of which switch is secured to a segmental core x' , passing through the bores of solenoids x^2 , which switch is capable of assuming a central position and extreme positions, with one end near one or the other of the solenoids. A switch y is shown upon each of the cars, the switch serving to close circuit through one or the other of the solenoids when thrown into one or the other of its extreme positions. One switch only, of course, need be operated. When this switch is in the central position, neither of the solenoids is energized, the spring x^3 , associated with the switches x then serving to restore the same to central positions when the circuit through the motors is completely opened. When the switches are in one extreme position, the motors are connected to run in one direction. When the switches are in the reversed extreme positions, the rotation of the motors is reversed. The solenoids constitute electromagnetic means for effecting the operation of the pole-changing switches, while the switches y , including their connections, each constitutes a unitary means for effecting the control of the said electromagnetic means.

In Fig. 2 I have shown supplemental rheostats z for initially controlling the operation of the traction-motors. In the apparatus shown in this figure the automatically-operated controller-actuating mechanism may open the circuit including each of the traction-motors. I have shown in this figure a conductor z' , which serves to unite the main rheostats upon each vehicle. The local-train circuit, including the battery k , coöperating with the controller-actuating mechanism, is omitted from Fig. 2 for the sake of clearness. The rheostat z shown upon car No. 1, for example, is adapted to close circuit through the main rheostats to start the motors, the train after being started then serving to operate the controller-actuating mechanism, after which the auxiliary rheostat may be thrown out of circuit.

There are devices of my invention that are adapted for use in other connections than with railway systems.

While I have herein shown and particularly described rheostats as comprising controllers for governing the operation of the traction-motors, I do not wish to be limited to this precise form of controller.

It is obvious that changes may readily be made in the apparatus of my invention without departing from its spirit, and I do not, therefore, wish to be limited to the precise arrangement shown; but,

Having thus described my invention, what I claim as new, and desire to secure by Letters Patent, is—

1. In a wheeled vehicle, the combination

with a shaft of the vehicle, of a gear-wheel q receiving rotary motion from the shaft and adapted thereby to be rotated in either direction, a second gear-wheel r receiving its motion from the gear-wheel q , a bevel-gear s receiving motion from the gear-wheel r , bevel-gears t, t , driven by the bevel-gear s , a ratchet v , and pawls carried by the bevel-gears t, t , and engaging the ratchet v whereby the latter is rotated in a single uniform direction irrespective of the direction of travel of the vehicle, substantially as described.

2. In a system of electric railway, the combination with a plurality of motor-cars in a single train, each having a controller for the corresponding propelling-motor, of means upon each of said cars operated by contact with the roadway for actuating a corresponding controller, and means upon a single car for operatively connecting the controller-actuating means with the controllers upon the several cars, substantially as described.

3. In a system of electric railway, the combination with a plurality of motor-cars in a single train, each having a controller adapted to graduate and regulate the current through a corresponding propelling-motor, of means upon each of said cars operated by contact with the roadway for actuating a corresponding controller, and means upon a single car for operatively connecting the controller-actuating means with the controllers upon the several cars, substantially as described.

4. In a system of electric railway, the combination with a plurality of motor-cars in a single train, each having a controller for the corresponding propelling-motor, of means upon each of said cars operated by contact with the roadway for actuating a corresponding controller, and a single actuating means for operatively connecting the controller-actuating means with the controllers at the same time, substantially as described.

5. In a system of electric railway, the combination with a plurality of motor-cars in a single train, each having a controller adapted to graduate and regulate the current through a corresponding propelling-motor, of means upon each of said cars operated by contact with the roadway for actuating a corresponding controller, and a single actuating means for operatively connecting the controller-actuating means with the controllers at the same time, substantially as described.

6. In a system of electric railway, the combination with a plurality of motor-cars in a single train, of controllers for the propelling-motors of the train, controller-actuating means operated by contact with the roadway, and means upon a single car for operatively connecting the controller-actuating means with the controllers upon the several cars, substantially as described.

7. In a system of electric railway, the combination with a plurality of motor-cars in a single train, of controllers serving to gradu-

ate and regulate the current through the propelling-motors, controller-actuating means operated by contact with the roadway, and means upon a single car for operatively connecting the controller-actuating means with the controllers upon the several cars, substantially as described.

8. In a system of electric railway, the combination with a plurality of motor-cars in a single train, of controllers for the propelling-motors of the train, a plurality of controller-actuating means operated by contact with the roadway, and a single actuating means for operatively connecting the controller-actuating means with the controllers at the same time, substantially as described.

9. In a system of electric railway, the combination with a plurality of motor-cars in a single train, of controllers serving to graduate and regulate the current through the propelling-motors, a plurality of controller-actuating means operated by contact with the roadway, and a single actuating means for operatively connecting the controller-actuating means with the controllers at the same time, substantially as described.

10. The combination with a wheeled vehicle provided with a propelling-motor and a controller for the motor, of a controller-actuating means, and means including an element having rolling contact with the roadway for operating the controller-actuating means, substantially as described.

11. The combination with a wheeled vehicle provided with a propelling-motor and a controller serving to increase and decrease the current through the propelling-motor, a controller-actuating means operated by contact with the roadway, and means whereby said actuating means may effect the operation of the controller in reverse directions, substantially as described.

12. The combination with a wheeled vehicle provided with a propelling-motor and a controller therefor, of a controller-actuating means operated by contact with the roadway, and means whereby the controller-actuating means may cause the operation of the controller in reverse directions while the vehicle is traveling in a single direction, substantially as described.

13. In an electric-railway system, a train comprising a plurality of motor-cars, each provided with a traction motor or motors and a motor-controller, means upon each motor-car operated by contact with the roadway for actuating the controller on that car, means upon each motor-car for operatively connecting the controller-actuating means with the controller, means for simultaneously controlling the operation of the said connecting means from any desired point on the train,

and auxiliary means for opening and closing the motor-circuits.

14. In an electric-railway system, a train comprising a plurality of motor-cars, each provided with a traction motor or motors and a motor-controller, means upon each motor-car operated by contact with the roadway for actuating the controller on that car, means upon each motor-car for operatively connecting the controller-actuating means with the controller, means for simultaneously controlling the operation of the said connecting means from any desired point on the train, and auxiliary means for controlling from any desired point on the train the connection between the motor-circuits and the source of supply.

15. In an electric-railway system, a train comprising a plurality of motor-cars, each provided with a traction motor or motors and a motor-controller, means upon each motor-car operated by contact with the roadway for actuating the controller on that car, means upon each motor-car for operatively connecting the controller-actuating means with the controller, and a train system comprising means for simultaneously controlling the operation of said connecting means and means for initially effecting the control of the traction-motors.

16. In an electric-railway system, a train comprising a plurality of motor-cars, each provided with a traction motor or motors and a motor-controller, means upon each motor-car operated by contact with the roadway for actuating the controller on that car, means upon each motor-car for operatively connecting the controller-actuating means with the controller, means upon each motor-car for controlling the circuit connection between the motor-circuits and the source of supply, and a train-control system for controlling from any desired point on the train the operation of said connecting means and said circuit-controlling means.

17. The combination with a wheel-vehicle provided with a propelling-motor and a controller therefor, of means operated by contact with the roadway for actuating the motor-controller, means for operatively connecting the controller-actuating means with the controller, and a control system comprising means for controlling the operation of the said connecting means, and auxiliary means for opening and closing the motor-circuits.

In witness whereof I hereunto subscribe my name this 9th day of December, A. D. 1899.

CARL HOCHENEGG.
